UNITED STATES PATENT OFFICE.

ALEXANDER CHURCHWARD, OF CHICAGO, ILLINOIS, ASSIGNOR TO GENERAL ELECTRIC COMPANY, A CORPORATION OF NEW YORK.

POLE-SHOE FOR DYNAMO-ELECTRIC MACHINES.

SPECIFICATION forming part of Letters Patent No. 723,989, dated March 31, 1903.

Application filed August 23, 1901. Serial No. 73,049. (No model.)

To all whom it may concern:

Be it known that I, ALEXANDER CHURCHWARD, a citizen of the United States, residing at Chicago, county of Cook, State of Illinois, 5 have invented certain new and useful Improvements in Pole-Shoes for Dynamo-Electric Machines, (Case No. 2,133,) of which the following is a specification.

This invention relates to dynamo-electric machines; and its object is to insure a more even distribution of the lines of force induced by the field-magnets, and thus prevent sparking at the brushes. It is well known that ordinarily the rotation of the armature tends 15 to crowd the lines of force in the field toward that side of the field-pole from which the armature is moving, a result which interferes with the efficiency of the machine. It is customary in some machines to overcome this 20 objection to a certain degree by slotting the field-magnet core on a plane transverse to the line of movement of the armature; but such machines generally have also a pole-shoe in order that as many lines of force as possible 25 may be utilized. Such a construction is shown in the United States Patent to Short, No. 607,609. The effect of the slot is reduced almost to a minimum by the shoe, because the latter completely encircles the end of the 30 magnet-core or pole-piece, so that there is a metallic path for the magnetic flux from one side of the pole to the other.

My invention consists in a pole-shoe slotted like the pole-piece to interpose the same air-gap in the shoe as in the pole-piece, and thus 35 cause both to work to their full effectiveness.

In the accompanying drawings, Figure 1 is

a side elevation of a portion of a multipolar machine embodying my invention. Fig. 2 is an end view of one of the pole-pieces, showing 40 the slotted shoe.

The pole-piece A is provided with the usual slot *a*, radial to the armature and parallel with the axis of rotation. The pole-shoe B is made in two U-shaped parts, which terminate at 45 the slot *a*, so that the continuity of the shoe is interrupted at that point, as it does not magnetically bridge the slot. It is evident that the shoe could be pieced out across the slot with some non-magnetic material, if this 50 should be found desirable for mechanical reasons.

What I claim as new, and desire to secure by Letters Patent of the United States, is—

1. A pole-shoe which only partially encircles the pole-piece.

2. A pole-shoe whose magnetic continuity is interrupted.

3. The combination with a slotted pole-piece, of a pole-shoe which does not magnetically bridge said slot.

4. The combination with a slotted pole-piece, of a pole-shoe which ends at the edge of the slot.

5. The combination with a slotted pole-piece, of a pole-shoe made in two U-shaped parts, each of which partially encircles the pole-piece and terminates at said slot.

In witness whereof I have hereunto set my hand this 19th day of August, 1901.

ALEXANDER CHURCHWARD.
